UNITED STATES PATENT OFFICE.

HENRY L. OLIPHINT, OF PAULS VALLEY, INDIAN TERRITORY.

MILLINER'S HAT-STAND.

SPECIFICATION forming part of Letters Patent No. 764,495, dated July 5, 1904.

Application filed December 3, 1903. Serial No. 183,589. (No model.)

To all whom it may concern:

Be it known that I, HENRY L. OLIPHINT, a citizen of the United States, residing at Pauls Valley, in the Chickasaw Nation, Indian Territory, have invented certain new and useful Improvements in Milliners' Hat-Stands; and I do declare the following to be a full, clear, and exact description of the invention, such as will enable others skilled in the art to which it app-
10 pertains to make and use the same.

My invention is an improved milliner's stand for holding a hat, bonnet, or the like for display and for securely retaining the same thereon, so that the hat or bonnet is not liable to fall or slip from the stand; and my invention consists in the construction and combination of devices hereinafter described and claimed.

In the accompanying drawings, Figure 1 is
20 a side elevation, partly in section, of a hat-stand embodying my improvements, showing the spreader-wires extended in full lines to engage the crown of a hat and showing them retracted in dotted lines to release the hat. Fig.
25 2 is partly a top plan view and partly a horizontal section of the same, taken on the plane indicated by the line *a a* of Fig. 1.

In the embodiment of my invention here shown I provide a base 1, from which rises a
30 standard-rod 2, at the upper end of which there is a circular cap 3. This cap serves to connect the upper ends of a series of spreader spring-wires 4 to the upper end of the standard. Each of the said spreader spring-wires
35 has its upper end bent outwardly, as at 5, and disposed radially, or substantially so, with reference to the standard and is then curved downwardly and outwardly, as at 6, to form a spreader portion adapted to fit in the crown
40 of a hat, the lower ends of the spreader-wires being attached to an adjusting-sleeve 7, which slides vertically on the standard 2. The spreader-wires are also connected together at a suitable distance from their lower ends by
45 a ring 8, through which the standard extends, the diameter of the ring being considerably in excess of that of the standard.

The standard is provided with stops 9 10, which coact with the opposite ends of the ad-

justing-sleeve 7 to limit the vertical move-
50 ment thereof upon the standard. The sleeve is provided in one side with a slot 11, and the standard has a spring-pressed pivotally-mounted detent 12 to engage the said slot, and thereby lock the adjusting-sleeve in a position substantially midway between the two stops 9 10. The said detent also coacts with the ends of the said sleeve to lock it against either of the stops 9 10, as will be understood.

The lower portions of the spring spreader-wires are bent spirally, as shown. The tension of the said spring-wires and their required shape may be maintained by partly turning the adjusting-sleeve to restore the spring spreader-wires to their required shape, 65 as will be understood.

In the operation of my invention a hat or the like article is placed on the rack, and the adjusting-sleeve is then moved as may be required to extend the upper outwardly-bowed portions of the spring spreader-wires to cause them to engage the crown of the hat, and thereby retain the hat firmly in place on the stand. To release the hat, the adjusting-sleeve must be drawn downwardly to retract 75 the outwardly-bowed upper portions of the spring-wires.

Where the hat is very flexible, it may be slipped from the stand without thus moving the adjusting-sleeve; but it will be understood 80 that under all conditions the tension of the spring spreader-wires within the crown of the hat will be sufficient to prevent the latter from becoming casually displaced.

From the foregoing description, taken in connection with the accompanying drawings, the construction and operation of the invention will be readily understood without requiring a more extended explanation.

Various changes in the form, proportion, 90 and the minor details of construction may be resorted to without departing from the principle or sacrificing any of the advantages of this invention.

Having thus fully described my invention, 95 what I claim as new, and desire to secure by Letters Patent, is—

A stand of the class described, comprising

a standard, spreader-wires connected at their upper ends to the upper end thereof, having their upper portions outwardly and downwardly bowed, and disposed substantially radially with reference to the standard and their lower portions bent spirally, the lower ends of the said wires converging toward the standard, a band connecting the wires together at a point below the outwardly and downwardly bowed portions thereof, and a sleeve, adjust-

able on the standard and to which the lower ends of the spreader-wires are attached.

In testimony whereof I have hereunto set my hand in presence of the subscribing witnesses.

HENRY L. OLIPHINT.
